DRAFTING INSTRUMENT FOR DRAWING
ELLIPSES

Robert G. Towle, San Francisco, Calif.

Application September 23, 1946, Serial No. 698,838

1 Claim. (Cl. 33—30)

1 The present invention relates to improvements in a drafting instrument for drawing ellipses. It consists of the combinations, constructions and arrangement of parts hereinafter described and claimed.

An object of my invention is to provide a drafting instrument that may be readily set up so as to draw an ellipse having predetermined major and minor axes. It is proposed to arrange the instrument in such a manner that the eccentricity or the difference in lengths of the major and minor axis of the ellipse may be varied, and thus various shapes of ellipses will result.

More specifically described, I provide an axial leg having a pointed end arranged to be pressed into a surface at the intersection of the major and minor axes of the ellipse to be drawn. This leg is adjustable to various inclinations relative to the surface, depending upon the shape of ellipse desired. An inscriber is guided by this axial leg during the drawing of the ellipse, and I find that best results are obtained when the inscriber is maintained parallel with the axial leg when the ellipse is being drawn.

It is further proposed in this invention to provide a pair of supporting legs that are arranged for holding the axial leg in the desired angular position relative to the surface on which the ellipse is to be formed. These supporting legs straddle the major axis of the ellipse, and I provide a pointer for facilitating the placing of the supporting legs equidistant on opposite sides of the major axis.

A still further object resides in the provision of a drafting instrument that is simple in construction, durable and efficient for the purpose intended.

Other objects and advantages will appear as the specification continues, and the novel features will be set forth in the claim hereunto appended.

For a better understanding of my invention, reference should be had to the accompanying drawing, forming part of this application, in which:

Figure 1 is a side elevation of my drafting instrument;

Figure 2 illustrates an ellipse drawn with the instrument as set up in Figure 1; and

Figure 3 is an end elevation of the instrument viewed from the right of Figure 1.

While I have shown only the preferred form of my invention, it should be understood that various changes, or modifications, may be made within the scope of the annexed claim without departing from the spirit thereof.

2

In carrying my invention into practice, I provide an axial leg A having a pointed end 1 that is designed to be pressed into a surface B on which an ellipse is to be drawn. Figure 2 discloses an ellipse C having its major and minor axes indicated by x—x' and y—y', respectively. The intersection of these axes is designated at o and the pointed end 1 is pressed into the surface at the intersection o. Prior to drawing the ellipse, it is advisable to lay out both axes and to plot the lengths thereof.

The top of the axial leg A has a pair of supporting legs D hinged thereto by a clamping screw 2. The angle a between the legs A and D may be adjusted and the screw 2 tightened to hold the legs in adjusted position.

Referring to Figure 3, it will be noted that the supporting legs have downwardly-diverging portions 3 terminating in parallel lower sections 4. The latter are slotted at 5 to receive point-carrying clamps 6. Adjusting screws 7 are provided for holding the clamps 6 in adjusted position. The points 8 should be arranged substantially vertically when the instrument is set up, and these points are made to be pressed into the surface B for anchoring the supporting legs in place.

A bar 9 is fixed to the clamps 6 and extends between the supporting legs near the bottoms of the latter. This bar forms a brace between the lower sections of the legs D. Figure 3 shows a pointer 10 as depending from this bar at its midpoint. In setting up the instrument, the pointer is placed along the prolongation of the major axis x—x' of the ellipse to be drawn, and this will position the points 8 equidistant on opposite sides of the major axis. In other words, the axial leg A will be positioned in a vertical plane passing through the major axis x—x'.

In order to add rigidity to the supporting legs, I have provided a web-like brace 11, which is secured to and extends between the upper portions 3 of the legs D, as clearly illustrated in Figures 1 and 3.

A sleeve 12 is rotatably and slidably disposed on the axial leg A and has a knurled end 12a to facilitate its turning by the draftsman. This sleeve is provided with a lug 13 to which an inscriber E is adjustably connected by means of a pair of parallel links 14. The latter are H-shaped, and the upper ends 14a of the H are pivoted to the lug 13, as at 15, while the lower ends 14b are pivoted to the inscriber at 16.

The inscriber E has a marker 17 secured thereto by means of a clamp 18 and set screw 19. The inscriber and marker are mounted in parallel re-

lation with the axial leg A, as shown in Figure 1. The links 14 allow the inscriber to be moved toward or away from the axial leg, while maintaining the former parallel with the latter. A clamping screw 20 may be tightened for holding the links in adjusted position.

It should be noted from Figure 1 that the inscriber retains its parallel relation with the axial leg A as the sleeve 12 is rotated. This will permit the point of the marker 17 to draw the ellipse C on the surface B, without tipping the marker on its side. As the inscriber moves around the axial leg A, the sleeve 12 will move up and down on that leg so that the marker will maintain contact with the surface upon which the ellipse is being drawn.

Having thus described the various parts of my drafting instrument, the operation thereof may be readily understood.

First, the draftsman draws the major and minor axes $x-x'$ and $y-y'$, respectively, and determines the lengths of these axes. At least the points x or x' and y or y' should be plotted to facilitate later steps. Next, the pointed end 1 of the axial leg A is pressed into the surface B at the intersection o of the two axes. The clamping screw 20 is released and the inscriber E is moved into a position where the marker 17 will register with the point y or y' . Thereupon, the set screw 20 is tightened.

Now the inscriber E is moved into a position so that the marker 17 will register with the major axis as suggested by the full and dotted positions in Figure 1. Without changing the adjustment of the inscriber, the draftsman moves the pointer 10 along the prolongation of the major axis until the marker 17 will register with the point x or x' . The draftsman now presses the points 8 into the surface B, and since the pointer 10 is located midway of the bar 9, the points 8 will be positioned equidistant on opposite sides of the major axis.

As the next step, the draftsman rotates the sleeve 12, allowing it to move up or down on the axial leg A as may be required to maintain the marker 17 in contact with the surface B. The marker 17 will pass through the points x , y , x' and y' and describe the ellipse.

In the event that the difference between the lengths of the major and minor axes is to be less than that shown in Figure 2, the supporting legs D are moved closer to the axial leg A, that is, the angle a is decreased. On the other hand, when the ellipse is to be given greater elongation, the supporting legs D are moved away from the axial leg A, thus increasing the angle a . In any case, the perpendicular distance between the axial

leg A and the marker 17, as suggested by the dimension $(o-y)$ or $(o-y')$ in Figure 1, must be set off first and the clamping screw 20 tightened. Then the axial leg is inclined to the proper amount that will cause the marker to pass through the points x and x' when the sleeve 12 is turned around the axial leg and the pointer 10 is maintained over the prolongation of the major axis.

I claim:

In a drafting instrument for drawing ellipses on a surface, an axial leg having a pointed end arranged to be pressed into the surface at the intersection of the major and minor axes of an ellipse to be drawn, a sleeve rotatably and slidably disposed on the axial leg, an inscriber mounted parallel to the axial leg, a pair of parallel links interconnecting the inscriber with the sleeve and made to retain the inscriber parallel with the axial leg as the inscriber is moved around the axial leg for drawing an ellipse on the surface, a pair of downwardly diverging legs rigidly connected together at their tops and hinged to the top of the axial leg for supporting the latter at various inclinations relative to the surface, the lower end portions of the diverging legs extending parallel to each other, a bar extending between the lower end portions and having point-carrying clamps at its extremities, adjusting screws for the clamps pivotally connecting the clamps and bar to the lower parallel end portions of the diverging legs, a pointer arranged on the bar midway between the ends of the point-carrying clamps, points carried by the clamps and lying in the same plane as the pointer, whereby the pointer and points can be swung as a unit into positions perpendicular to the surface, the pointer being placed on the major axis.
